UNITED STATES PATENT OFFICE.

JOHAN LUDVIG JÖNSSON, OF STOCKHOLM, SWEDEN, ASSIGNOR TO THE
AKTIEBOLAGET SEPARATOR, OF SAME PLACE.

AUTOMATIC SPEED-REGULATOR FOR STEAM-TURBINES.

SPECIFICATION forming part of Letters Patent No. 554,425, dated February 11, 1896.

Application filed November 8, 1895. Serial No. 568,300. (No model.)

To all whom it may concern:

Be it known that I, JOHAN LUDVIG JÖNSSON, engineer, a subject of the King of Sweden and Norway, residing at Stockholm, Sweden, have 5 invented certain new and useful Improvements in Automatic Speed - Regulators for Steam-Turbines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention has for its object to automatically regulate the speed of the turbine by regulating the size of the supply-port by the speed-revolution of the turbine.

It consists, broadly considered, in supporting the turbine upon the shaft or connecting it therewith so that it may have a lateral movement and in one of its extreme positions leave the supply-port full open and in the other extreme position closed entirely, the 25 turbine being held normally in the first-mentioned position, and providing devices which, under the action of centrifugal force in the rotation of the turbine proportionate to the speed of revolution, act upon and move the 30 turbine downward to more or less close the inlet-port.

I will first describe the embodiment of my invention as illustrated in the accompanying drawings, and then particularly point out the 35 invention in the claims.

In the drawings, Figure 1 is a vertical section on the line 1 1 of Fig. 2. Fig. 2 is a section on the line 2 2, Fig. 1, with plate I removed. Fig. 3 is a section on the line 3 3, 40 Fig. 2.

A is the shaft of the turbine; B, the casing; C, the plate or frame holding the buckets or vanes c. This plate has centrally the flange portion D partially cut away, forming the recess d. In this recess is a coil-spring d', one end resting on or secured to the flange portion D at the upper end of recess d and the other end on or secured to a collar E, secured to shaft A. The flange portion D has a slot 45 d³, through which a pin d², secured to the shaft A, passes. The bucket or vane frame C has

at its outer end the upwardly-extending flange F, of extent equal to the inlet-port G. The inner surface of the casing B is formed eccentric with the frame C, so that at one portion, contiguous to the inlet-port, the flange F above the bucket and flange f' below the bucket fit snugly against the said surface, while at that portion contiguous to the outlet-port H a space is left between these parts, the first 55 condition being to prevent the escape of steam or other gas or vapor in entering the bucket at the inlet-port and the other to allow it to readily discharge at the outlet-port.

I is a plate secured to the shaft by pin d², 60 the frame or plate C being at its inner or central portion cut away, as at c², and the plate I so formed at one or more points by depending flanges i as to form between it and the frame C a pocket i², decreasing in height from 65 the shaft outward and with an inclination toward the shaft. In these pockets, of which there may be any number, six being shown, are placed balls or spheres J.

From the foregoing description it will be 70 clearly seen that the frame C is capable of a vertical movement of limited extent upon the shaft A, and is held normally in the position shown in Fig. 1 by the spring d'.

When the turbine is revolved, the centrifugal force tends to throw the balls J outward, and when the speed is sufficient to overcome the weight of the balls they commence to move outward, and, the plate I being fixed and the pocket i² of decreasing height outward, the balls force the turbine downward upon the shaft A, the extent of outward movement of the spheres J being dependent upon the speed of revolution of the turbine. Thus the downward movement of the turbine is dependent upon its speed of rotation.

Initially and when the turbine is at rest the top of the inlet-port coincides with the bottom of flange F. In the revolution of the turbine, when, as described, the turbine moves 95 downward, the flange F covers the inlet-port by an amount dependent upon the extent of its drop, and thus dependent upon its speed of rotation, until finally, when it has moved downward its utmost, the port is entirely 100 closed. This downward movement is against the spring d', and therefore whenever the

speed falls and the ball moves inward the spring moves the turbine on the shaft in a reverse direction, again opening the port.

This device is adapted to a turbine driven by any means, whether steam, water, air, or any other power.

I do not intend to limit myself to the specific embodiment of my invention illustrated by the accompanying drawings and hereinbefore described, except as the same may be specifically claimed.

Having now fully described my invention, what I claim, and desire to protect by Letters Patent, is—

15 1. In combination with a turbine wheel, a shaft upon which said wheel is secured so as to have a rotary movement and a movement along said shaft, an inlet-port for said turbine, and means thrown into action by the 20 rotation of said turbine and adapted when rendered active to move said turbine along said shaft an extent dependent upon the speed of rotation of the turbine, the turbine being adapted in its movement in one direction upon 25 said shaft to close said inlet-port, and in the other direction to open it.

2. In combination with a turbine wheel, a shaft upon which said wheel is secured so as to have a rotary movement and a movement 30 along said shaft, an inlet-port for said turbine, and means thrown into action by the rotation of said turbine and adapted when rendered active to move said turbine along said shaft an extent dependent upon the speed of rotation 35 of the turbine, the turbine being adapted in its movement in one direction upon said shaft to close said inlet-port, and in the other direction to open it, and a spring or equivalent device against which said turbine acts in its movement along the shaft in one direction upon said shaft to close, and in the other direction to open the said inlet-port.

3. In combination with a turbine wheel, a shaft upon which said wheel is secured so as to have a rotary movement and a movement along said shaft, an inlet-port for said turbine, a peripheral flange upon said wheel of extent 45 substantially equal to the inlet-port, and means thrown into action by the rotation of said turbine and adapted when rendered active to move said turbine along said shaft an 50 extent dependent upon the speed of rotation of the turbine, the peripheral flange being adapted in the movement of the turbine in one direction on said shaft to close said inlet-port, and in the other to open it.

55 4. In combination with a turbine wheel, a shaft upon which said wheel is secured so as to have a rotary movement and a movement along said shaft, an inlet-port for said turbine, a peripheral flange upon said wheel of extent 60 substantially equal to the inlet-port, and means thrown into action by the rotation of said turbine and adapted when rendered active to move said turbine along said shaft an extent dependent upon the speed of rotation 65 of the turbine, the peripheral flange being adapted in the movement of the turbine in

one direction on said shaft to close said inlet-port, and in the other direction to open it, and a spring or equivalent device against which said turbine acts in its movement along the 70 shaft in one direction.

5. In combination with a turbine wheel, a shaft upon which said wheel is secured so as to have a rotary movement and a movement along said shaft, an inlet-port for said turbine, 75 a peripheral flange upon said wheel of extent substantially equal to the inlet-port, and means thrown into action by the rotation of said turbine and adapted when rendered active to move said turbine along said shaft an 80 extent dependent upon the speed of rotation of the turbine, the peripheral flange being adapted in the movement of the turbine in one direction on said shaft to close said inlet-port, and in the other direction to open it, and a spring or equivalent device against which said turbine acts in its movement along the 85 shaft in one direction, said spring tending to hold said turbine free from covering said inlet-port.

6. In combination with a turbine wheel, a shaft upon which said wheel is secured so as to have a rotary movement and a movement along said shaft, a plate or frame secured so as to have no movement along said shaft, 90 there being between which plate and the turbine wheel radial passages, spheres in said passages, and an inlet-port, the turbine wheel being adapted in its movement in one direction upon said shaft to close, and in the other 95 direction to open the said inlet-port.

7. In combination with a turbine wheel, a shaft upon which said wheel is secured so as to have a rotary movement, and a movement along said shaft, a plate or frame secured so 100 as to have no movement along said shaft, there being between which plate and the turbine wheel radial passages, spheres in said 105 passages, and an inlet-port, the turbine wheel being adapted in its movement in one direction upon said shaft to close, and in the other 110 direction, to open the said inlet-port, and a spring or equivalent device against which said turbine acts in its movement along the shaft in one direction.

8. In combination with a turbine wheel, a shaft upon which said wheel is secured so as to have a rotary movement and a movement along said shaft, a plate or frame secured so as to have no movement along said shaft, 115 there being between which plate and the turbine wheel radial passages, spheres in said 120 passages, and an inlet-port, the turbine wheel being adapted in its movement in one direction upon said shaft to close, and in the other 125 direction to open the said inlet-port, and a spring or equivalent device against which said turbine acts in its movement along the shaft in one direction, said spring tending to hold 130 said turbine free from covering said inlet-port.

9. In combination with a turbine wheel, a

shaft upon which said wheel is secured so as to have a rotary movement and a movement along said shaft, said turbine wheel having a peripheral flange, a plate or frame secured 5 so as to have no movement along said shaft, there being between which plate and the turbine wheel radial passages, spheres in said 10 passages, and an inlet-port, the peripheral flange of the turbine wheel being adapted in its movement in one direction along said shaft to close, and in the other direction to open, 15 said inlet-port.

10. In combination with a turbine wheel, a shaft upon which said wheel is secured so as to have a rotary movement and a movement 15 along said shaft, said turbine wheel having a peripheral flange, a plate or frame secured so as to have no movement along said shaft, there being between which plate and the turbine 20 wheel radial passages, spheres in said passages, and an inlet-port, the peripheral flange of the turbine wheel being adapted in its movement in one direction along said shaft to close, and in the other direction to open, 25 said inlet-port, and a spring or equivalent

device against which said turbine acts in its movement along the shaft in one direction.

11. In combination with a turbine wheel, a shaft upon which said wheel is secured so as to have a rotary movement, and a movement 30 along said shaft, said turbine wheel having a peripheral flange, a plate or frame secured so as to have no movement along said shaft, there being between which plate and the turbine wheel radial passages, spheres in said 35 passages, and an inlet-port, the peripheral flange of the turbine wheel being adapted in its movement on said shaft in one direction to close, and in the other direction to open, the said inlet-port, and a spring or equivalent 40 device against which said turbine acts in its movement along the shaft in one direction, said spring tending to hold said turbine free from covering said inlet-port.

In testimony whereof I affix my signature 45 in presence of two witnesses.

JOHAN LUDVIG JÖNSSON.
